(57) **CLAIM**

The ornamental design for a pendant light, as shown and described.

DESCRIPTION

FIG. 1 is a perspective view of a pendant light showing the new design;

FIG. 2 is a side elevational view of the pendant light as shown in FIG. 1;

FIG. 3 is an opposite side elevational view of the pendant light as shown in FIG. 1; and,

FIG. 4 is a bottom view of the pendant light as shown in FIG. 1.

Features shown in dashed lines immediately adjacent the shaded areas or adjacent the solid lines represent the bounds of the claim and all other dashed lines are for illustrative purposes only. None of the dashed lines form a part of the claimed design.
